PUMP BASE

Linus E. Russell, Springfield, Ohio, assignor to Peters & Russell, Inc., Springfield, Ohio, a corporation of Ohio

Application September 8, 1958, Serial No. 52,539

Term of patent 14 years

(Cl. D65—1)

Fig. 1 is a side view of a pump base embodying my design;

Fig. 2 is a top plan view;

Fig. 3 is a front view.

The dotted line disclosure of a pump is for illustrative purposes only.

I claim:

The ornamental design for a pump base, substantially as shown and described.
